UNITED STATES PATENT OFFICE.

EUGENE POTTER, OF WINSTED, CONNECTICUT.

DESIGN FOR AN EMBROIDERY-SILK-HOLDER CARD.

SPECIFICATION forming part of Design No. 29,722, dated November 22, 1898.

Application filed October 24, 1898. Serial No. 694,484. Term of patent 7 years.

To all whom it may concern:

Be it known that I, EUGENE POTTER, of Winsted, in the county of Litchfield and State of Connecticut, have invented and produced a new Design for an Embroidery-Silk-Holder Card; and I do hereby declare the following, when taken in connection with the accompanying drawing, and the letters of reference marked thereon, to be a full, clear, and exact description of the same, and which said drawing constitutes part of this specification, and represents a perspective view of an embroidery-silk-holder card embodying my design.

This invention relates to a design for an embroidery-silk-holder card; and it consists in the conformation as hereinafter described, and shown in the accompanying illustration.

The card A has a notch B at one end and at the opposite end two parallel slots C D, extending from the circular openings E F 20 through the end of the card, forming three fingers G, H, and I at that end of the card, all as shown in the accompanying illustration.

I claim—

The design for an embroidery-silk-holder 25 card, as herein shown and described.

In testimony whereof I have signed this specification in the presence of two subscribing witnesses.

EUGENE POTTER.
